(Cl. D33—7)

To all whom it may concern:

Be it known that I, Frank P. Fletcher, a citizen of the United States, residing at Pasadena, in the county of Los Angeles and State of California, have invented a new, original, and ornamental Design for a Desk With External Shelves, of which the following is a specification, reference being had to the accompanying drawing, in which:

Fig. 1 is a perspective view of a desk, showing my new design;

Fig. 2 is a top plan view;

Fig. 3 is a bottom plan view;

Fig. 4 is a side elevational view;

Fig. 5 is a front elevational view; and

Fig. 6 is a rear elevational view thereof.

I claim:

The ornamental design for a desk with external shelves, as shown.

FRANK P. FLETCHER.
